UNITED STATES PATENT OFFICE.

WILLIAM SCHIERDING, OF SPOKANE, WASHINGTON.

DIRIGIBLE LAMP.

Application filed February 18, 1922. Serial No. 537,476.

To all whom it may concern:

Be it known that I, WILLIAM SCHIERDING, a citizen of the United States, residing at Spokane, in Spokane County and State of Washington, have invented certain new and useful Improvements in Dirigible Lamps, of which the following is a specification.

My present invention relates to improvements in dirigible lamps for use as spot lights or search lights on automobiles, motor boats, &c., which may be manipulated or turned in various directions for directing the light rays as desired.

26 The invention contemplates a compact arrangement of the operating parts whereby the lamp may be mounted to swivel in a horizontal plane, and also be turned in a vertical plane or tilted, and also includes 29 means, involving a flexible connection, for actuating the device, whereby the lamp may be mounted at convenience and in desirable locations, as will hereinafter be more specifically pointed out and claimed.

25 In the accompanying drawings I have illustrated one complete example of the physical embodiment of my invention where-in the parts are combined and arranged according to the best mode I have thus far 30 devised for the practical application of the principles of my invention.

Figure 1 is an exterior, face view, in elevation of the lamp mounted for operation.

33 Figure 2 is a similar view, but with parts in section to disclose the operating parts of the lamp.

Figure 3 is a view in side elevation of the lamp, partly broken away to illustrate the cord or wire that permits portable use 40 of the electric lamp.

Figure 4 is a vertical sectional view through the lamp showing also in dotted lines the tilted positions of the lamp.

Figure 5 is a view in perspective of the 45 lamp bracket.

Figure 6 is a perspective view of a brake member or retarder, which also performs the functions of an anti-rattler.

50 The lamp indicated as a whole by the numeral 1 is or may be of usual and standard type, and is capable of being turned on a swivel in a horizontal plane, and also tilted, up or down, in a vertical plane. At the underside of the circular or cylindrical lamp 55 is affixed a base plate 2 conforming to the shape of the lamp casing and of sufficient

width to provide a stable support for the lamp, the plate being secured to the lamp casing by screws as 3.

The base plate 2, as best seen in Figures 60 2 and 4 is fashioned with a central rib 4, aligned with the longitudinal axis of the lamp, and provided with an arcuate bottom face on a radius struck from the center of the lamp casing. The rib is fashioned with 65 exterior groove 4', and along one side of this groove are provided rack teeth 5, forming an arcuate rack, as indicated in Figure 4. At its edges the base plate is provided with inwardly extending, opposite flanges 70 6 providing grooves, also of arcuate shape and on an arc struck from the lamp center.

The base plate is supported upon a swivel head 7 that is circular in cross section, and provided with a transverse groove at its 75 upper end conforming to and adapted to receive the guide rib 4. Side flanges 8 are provided on the head and project into the grooved flanges 6 of the base plate, and it will be apparent that the base plate on the 80 lamp, as the lamp is tilted in a vertical plane, will be guided in the grooved head and by the flanges of the head in the grooved flanges of the plate, the relative movement 85 being accomplished as will be described.

The swivel head is seated in a stationary casing or cup 9, and the lamp and head are movable relative to this casing, the swivel head being guided in horizontal swivel movement by the annular shoulder 10 on 90 the head resting on the top edge of the casing.

To retain the head in its casing, and also for the purpose of preventing wobbling or loss of motion of the swivel head in its casing, I utilize in an annular, exterior groove 11 of the head, a brake member 12, as best seen in Figure 6. The brake member is of arcuate shape conforming to the diameter of the groove 11 into which it is fitted, and is 95 retained in the groove by means of a set screw 13, passed from the outside of the casing through an opening therein, and also through a threaded lug 14 at the inner side of the brake band. The ends of the brake 105 band, as at 15, are thinned and resilient, in order that they may be brought into close frictional contact with the inner wall of the groove in the head. The lug 14 conforms to the shape of the groove and fits snugly 110 therein to act as a guide for the grooved head, and the resilient ends 15 of the brake

band or brake arms bear with sufficient friction on the grooved head to hold the head from turning within the casing, except when power is applied, as will be described.

5 The casing 9 is supported in the bracket ring 16, which has an arm 17 longitudinally adjusted, and also capable of being turned to adjusted position in the tubular bracket arm 18. The arm 18 has an angularly disposed sleeve 19 that is fitted to a support, as one of the side bars of an automobile wind shield (not shown), and the parts 16, 17, 18 thus form a laterally extending support for the lamp.

15 Both the horizontal, and the vertical or tilting movement of the lamp are accomplished from the same shaft 20, which is arranged transversely of the casing 9, passing therethrough and the shaft is supported in 20 bearings 21 in the wall of the casing and by an intermediate bearing 21' in the interior of the casing. A comparatively wide bevel-gear 22 is fixed on shaft 20 within the casing 9, and engages normally with a complementary rack ring 23 on the lower end of the swivel head 7. Within the swivel head is journaled a vertically disposed stub shaft 24 on which the bevel pinion 25 is fixed, and with this bevel pinion the gear 22 is also 30 normally engaged. At its upper end the stub shaft has a fixed rack wheel 26 located in the groove in the rib of the base plate and in engagement with the arcuate rack 5 on the grooved rib.

35 The operating shaft 20 is actuated through the flexible shaft section 27 from the hand wheel 28 and its shaft 29, the latter being journaled in bearings as 30 and coupled in suitable manner to the flexible shaft section.

40 The flexible shaft section may be of suitable length, and is designed to permit attachment of the shaft bearings 30 in location in order that the hand wheel 28 may be positioned for ready access by the automobile driver,

45 regardless of the point of attachment of the lamp bracket to the windshield. Thus the lamp may be attached to the windshield, and the hand wheel located near the lamp, as in Figures 1 and 2, or the lamp may be provided with a longer flexible shaft-section to permit attachment of the hand wheel nearer the driver of the car.

For turning the lamp the shaft 20, and its wheel 22, by engagement with wheel 25 and 55 rack ring 23, are manipulated from the hand wheel 28. For tilting the lamp, the shaft 20 is shiftable longitudinally in order that the wheel 22 may be released from wheel 25 and ring 23, and the shaft may be shifted by a 60 pull on the hand wheel 28.

On the shaft 20 between the intermediate bearing 21' and the casing are interposed clutch members including a loose bevel pinion 31, shiftable with the shaft 20 that is 65 adapted to be pulled into engagement with

teeth 32 of the bottom of the casing and also with rack ring 23 of the swivel head. This loose pinion 31 by its engagement with the fixed teeth 32 and rack ring 23 holds the latter, and the swivel head against turning 70 in a horizontal plane when the lamp is tilted. Between the loose pinion and the intermediate bearing are a tight, smaller pinion 33 and a spring 34, the latter coiled about shaft 20, and adapted normally to hold the shaft 20, wheel or pinion 33, and pinion 31, in normal position as in Figure 2. When the shaft 20 is pulled to the right in Figure 2, against tension of spring 34, the pinion 31 first locks the swivel head against turning, 80 while the pinion 33 is caused to clutch the larger rack wheel 25 of stub shaft 24. Now as the hand wheel 28 is turned the stub shaft 24 is revolved, and with it the larger rack wheel 25 and smaller rack wheel 26. As the latter is in engagement with the rack 5 of the lamp base, the lamp base and lamp may be tilted to positions between the extreme positions indicated by dotted lines in Figure 4. When the lamp has been tilted to 90 properly adjusted position, the hand wheel is released, the spring 34 returns the shaft 20 to normal position, and the gear 22 engages the rack ring 23 and rack wheel 25 to hold the latter, thus holding the lamp as desired. 95 By this means the lamp may be turned horizontally on its swivel joint, and tilted in a vertical plane, for a variety of uses.

In some instances the lamp may be used 100 as a portable lamp and for this purpose the reflector 35 and electric bulb 36 are detachably secured within the nut 37 fixed at the rear of the lamp by threading on the head 38 of the bulb. A comparatively long wire or 105 cord 39 is connected with the electric light and wrapped around a shell 40 within the lamp casing, one end of the wire of course being connected with a source of supply. By unscrewing the nut 37 the bulb, reflector, &c., may be detached from the lamp casing 110 and used as a portable lamp, the wire 39 being unwound from its shell to permit carrying the lamp away from its casing.

Having thus fully described my invention, 115 what I claim as new and desire to secure by Letters Patent is:—

1. The combination in a dirigible lamp, with its fixed base plate and an arcuate rack-rib thereon, of a casing, a head in said casing and grooved to receive said rib, means for guiding said rib, a stud shaft in the head and a rack wheel thereon engaging the rack rib, and means for turning said shaft to tilt the lamp. 120

2. The combination in a dirigible lamp, 125 with its base plate and an arcuate rack-rib thereon, of a casing, a head in said casing having a transverse groove to receive said rib, grooved flanges on the head and complementary guide flanges on said plate, a 130

stud shaft in the head having a rack wheel engaging the rack-rib, and means for turning said shaft.

3. The combination in a dirigible lamp with its base plate and an arcuate rack-rib thereon, of a casing, a head swiveled in said casing and provided with a transverse groove to receive said rib, a stud shaft in the head having a rack wheel to engage the rack rib, a rack ring on the head, a second rack wheel on said shaft, and shiftable means for selectively engaging said rack ring or the latter rack wheel for turning or tilting the lamp.

15 4. The combination in a dirigible lamp with a casing, and a swiveled head therein having a rack ring, of a shiftable shaft, a toothed portion in the casing, and a loose gear on said shaft adapted to engage said ring and toothed portion to lock said head, a stud shaft in the head and means thereon

for tilting the lamp, a rack wheel on said shaft, and a pinion on the shiftable shaft to engage said rack wheel, and brake means for retaining the lamp.

25

5. The combination in a dirigible lamp with a casing, of a swiveled head having a rack ring, a shiftable shaft having spaced gear wheels adapted to selectively engage said rack ring, a loose gear wheel on said shaft, a stud shaft in the head having connections therefrom to tilt the lamp, a rack wheel on the stud shaft adapted for selective engagement by said loose gear or one of said spaced gears, and a toothed face in 30 the casing adapted to co-act with the other spaced gear, whereby the shiftable shaft may be moved longitudinally and turned for the purpose described.

35 In testimony whereof I affix my signature.

40 WILLIAM SCHIERDING.
